UNITED STATES PATENT OFFICE

146,489

DESIGN FOR A FLY-SWATTER BLADE

Charles A. Sivon, Painesville, Ohio

Application November 30, 1945, Serial No. 124,243

Term of patent 14 years

(Cl. D31—3)

To all whom it may concern:

Be it known that I, Charles A. Sivon, a citizen of the United States, in the city of Painesville, county of Lake, and State of Ohio, have invented a new, original, and ornamental Design for a Fly-Swatter Blade, of which the following is a specification, reference being had to the accompanying drawing, forming a part thereof:

Figure 1 is a top plan view of a fly swatter blade, showing my new design;

Figure 2 is an edge view;

Figure 3 is a bottom plan view; and

Figure 4 is a cross-sectional view taken along the line 4—4 of Figure 1.

I claim:

The ornamental design for a fly-swatter blade, substantially as shown.

CHARLES A. SIVON.
